C. LOBNER

TIE CASE OR CONTAINER

Filed Jan. 22, 1927

INVENTOR
CHARLES LOBNER
BY
Howard C. Thompson
ATTORNEY

UNITED STATES PATENT OFFICE.

CHARLES LOBNER, OF NEW YORK, N. Y.

TIE CASE OR CONTAINER.

Application filed January 22, 1927. Serial No. 162,859.

This invention relates to cases or containers for neckties, such for example as four-in-hand, bow ties and the like or for any other elongated fabric body or article, 5 requiring careful packing to avoid creasing or wrinkling thereof; and the object of the invention is to provide a case or container in which neckties and the like may be placed in an extended or folded position in such 10 manner that the ends of the tie or ties or other articles, and particularly the ends of neckties, may be packed and carried without danger of wrinkling or creasing except where the tie may be folded at the neckband 15 portion thereof; a further object being to provide adjustable means for supporting one or more stacks of ties in the case or container; a further object being to provide means for protecting and retaining the ends 20 of the ties mounted in the case or container in predetermined position; a further object being to provide a case composed of a plurality of foldably connected parts, with means for retaining said parts in folded position to form said case, and said parts being 25 adapted to be extended to facilitate the placement of ties in the case, and the removal of ties therefrom; and with these and other objects in view, the invention consists 30 in a device of the class and for the purpose specified, which is simple in construction, efficient in use, and which is constructed as hereinafter described and claimed.

The invention is fully disclosed in the 35 following specification, of which the accompanying drawing forms a part, in which the separate parts of my improvement are designated by suitable reference characters in each of the views, and in which:—

40 Fig. 1 is a perspective view of a case made according to my invention, with the parts in a partially extended position, and illustrating the method of its use.

Fig. 1^a is a small view showing the case in 45 a fully extended position.

Fig. 2 is a perspective view of the case shown in Fig. 1 in a partially folded or collapsed position.

Fig. 3 is an end view of the case shown in 50 Figs. 1 and 2 in a folded position; and,

Fig. 4 is a perspective view of a part of a suitcase or other container, showing means for supporting and retaining ties and the like in predetermined position in connection therewith.

In Figs. 1 to 3 inclusive, I have shown one method of carrying my invention into effect, which consists in providing a case or body 5 which may be composed of fabric of any kind or class and including leather and imitation leathers, or a combination of different materials, especially as regard to the inner and outer faces thereof, and these materials may be entirely flexible or may be semi-rigid as may be desired. 60

The case comprises a central body 6 which is of greater length than width, and is provided at its ends with flaps 7 foldable onto the body 6 on the lines 7^a, and the sides of the body 6 are provided with flaps 8 foldable onto the body 6 and the flaps 7 on the lines 8^a. The central outer edges of the flaps 7 have one part 9 of snap fastening devices adapted to engage the other part 9^a thereof on the inner face of the central body 6 to retain the flaps 7 against displacement and to divide the side portions of the flaps 7 to form two pockets at each end of the case or the central body portion 6 thereof, into which the ends of neckties, bow ties 80 and the like 10 are adapted to be placed, said pockets serving to retain the ends of the ties against displacement. The outer sides of the pockets are closed when the flaps 8 are folded inwardly upon the flaps 7, and the 85 body 6 as partially seen in Fig. 1, and as seen in Fig. 2.

The outer faces of the flaps 8 adjacent the lines of folding 8^a are provided with two snap fastener parts 11—11^a in common alignment and adapted to be coupled together as 90 seen in Fig. 3, when the entire case is folded centrally and longitudinally of the body 6 to bring the flaps 8 one upon the other as seen in Fig. 3 of the drawing. 95

I also provide centrally and transversely of the body 6, a strap 12, the central portion of which is secured to the central part of the body 6 as seen at 13. The ends of the strap 12 are provided with a plurality of socket members 14 of snap fastening devices adapted to engage the other part of a snap fastening device, secured to the central body 10 adjacent the lines of folding 8^a. In other words, either one of the three devices 14 shown may 100 engage a single device at each side of the body 6. 105

It will be understood that the ends of the strap 12 pass over the central portions in the packing and transportation of neckties, 110

bow ties and similar articles of apparel, and have provided a definite means of maintaining the ties in proper condition when in transportation, and especially for traveling men, tourists and others. It will also be understood that my improved case may be used by the manufacturer or manufacturers of ties and like merchandise as a container, and further as a means for stimulating the sale of one or more ties, and providing in addition to the sale of the ties, the sale of a case suitable for transportation of ties and like articles.

Likewise, my invention is not necessarily limited to the construction or production of a case itself, as the same structure may be incorporated in and as part of a suitcase or other container. In Fig. 4 of the drawing, I have indicated at 15, a part of a suitcase, 20 16 representing the cover thereof in an open position to show its inner face. In practice, I provide the end portions of the inner face of the cover 16 with members 17 divided centrally as seen at 18 by stitching or in any 25 other desired manner to form pockets 19 into which the ends of neckties or other articles are adapted to be placed. Secured centrally of the inner face of the cover 16 as seen at 20, is a strap 21 similar to the 30 strap 12 shown in Fig. 1 of the drawing. The ends of the strap have snap fastening devices 22 for the adjustment of said ends to compensate for the number of ties supported beneath each end of the strap member 35 and into pockets 19.

The sides of the cover 16 may also be provided on the inner face with flaps 23 foldable inwardly upon the members 17 to retain the ties against accidental displacement. 40 These members may constitute the usual flaps employed in suitcases of conventional form or may be specially constructed, and provided with snap fastening devices 24 engaging similar devices 25 on the members 17 45 to retain the flaps 23 in closed position.

Many other uses and adaptations of the invention will present themselves to those skilled in the art, the showing in Fig. 4 of the drawing being merely illustrative of the 50 possible applications and uses of my invention. It will also be understood that the case, as a separate article of manufacture as seen in Figs. 1 to 3 inclusive, and especially the outer face thereof, may be ornamented 55 or designed to produce an attractive, rich and ornamental appearance, as in other cases such as cases for toilet articles, now in common use.

While I have shown and described certain 60 methods of carrying my invention into effect, it will be understood that I am not necessarily limited to the details of construction herein shown and described, and various changes therein, and modifications thereof, 65 may be made within the scope of the ap-

pended claims, without departing from the spirit of my invention or sacrificing its advantages.

Having fully described my invention, what I claim as new and desire to secure by Letters Patent, is:—

1. A case of the class described comprising an elongated, central body, flaps at the ends of said body and foldable onto one face thereof, means for securing said flaps to said body, other flaps at the sides of said body and foldable onto the first named flaps and said body, said case with the flaps folded thereonto, being folded centrally to bring the side flaps adjacent each other, means for securing said flaps together to close the case, the central inner face of the body being provided with a strap having free end portions extending to the sides of said body, and means for adjustably securing the ends of said strap. 80

2. An article of manufacture of the class described comprising an elongated body, means at the ends of said body and foldable onto the central portion of said body and attached thereto in such manner as to form pockets into which the opposite ends of articles to be mounted on said central body are adapted to be placed, and means centrally of the body for retaining the central portion of such articles against displacement from said body. 90

3. An article of manufacture of the class described comprising an elongated body, means at the ends of said body and foldable onto the central portion of said body and attached thereto in such manner as to form pockets into which the opposite ends of articles to be mounted on said central body are adapted to be placed, means centrally of the body for retaining the central portion of such articles against displacement from said body, said last named means being adjustably coupled with the central body, and means at the side of said body foldable thereonto to encase the articles therein and close the sides of said pockets. 100

4. An article of manufacture of the class described comprising an elongated body, means at the ends of said body and foldable onto the central portion of said body and attached thereto in such manner as to form pockets into which the opposite ends of articles to be mounted on said central body are adapted to be placed, means centrally of the body for retaining the central portion of such articles against displacement from said body, said last named means being adjustably coupled with the central body, means at the side of said body foldable thereonto to encase the articles therein and closing the sides of said pockets, said body being foldable centrally to bring the last named means one upon the other, and means for securing the parts together in such folded position. 110 120 130

5. A case of the class described comprising an elongated central body, flaps at the ends of said body and foldable onto one face thereof, means for securing the central portion of said flaps to said body to form between said flaps and body two pockets, other flaps at the sides of said body and foldable onto the first named flaps and said body and forming the sides of said pockets, said case with the flaps folded thereonto being foldable centrally to bring the side flaps adjacent each other, and means for securing said side flaps together to close the ends. 15
- 10 6. A case of the class described comprising an elongated central body, flaps at the ends of said body and foldable onto one face thereof, means for securing the central por- 20

tion of said flaps to said body to form between said flaps and body two pockets, other flaps at the sides of said body and foldable onto the first named flaps and said body and forming the sides of said pockets, said case with the flaps folded thereonto being foldable centrally to bring the side flaps adjacent each other, and means for securing said side flaps together to close the ends.

In testimony that I claim the foregoing as my invention I have signed my name this 18th day of January, 1927.

CHARLES LOBNER.
